UNITED STATES PATENT OFFICE.

CASPAR METTLER, OF NEW HAVEN, CONNECTICUT, ASSIGNOR TO ROBERT B. SEWARD,
OF BROOKLYN, NEW YORK.

HOLDER FOR DRINKING-CUPS.

1,112,824.

Specification of Letters Patent.

Patented Oct. 6, 1914.

Application filed February 9, 1912. Serial No. 676,623.

To all whom it may concern:

Be it known that I, CASPAR METTLER, a citizen of the United States, and resident of New Haven, in the county of New Haven and State of Connecticut, have invented a new and useful Improvement in Holders for Drinking-Cups, of which the following is a specification.

The object of my invention is to provide a holder for use in connection with drinking cups having unsealed sides, said holder serving as a means for temporarily sealing the sides of the cups and supporting the walls of the cups when filled.

15 A further object is to provide a holder of the above character which will be easily manipulated and into which the cups may be readily inserted and as readily removed.

A practical embodiment of my invention is 20 represented in the accompanying drawings, in which,

Figure 1 represents the holder in top plan with my improved drinking cup inserted into position therein ready to have its side 25 edges pinched together to seal the side of the cup, Fig. 2 is a view in side elevation of the same, the cup being shown in dotted lines in its collapsed position and in full lines in its distended position, certain of the parts being 30 broken away to more clearly show the parts beneath the same, Fig. 3 is a horizontal section taken in the plane of the line A—A of Fig. 2, and Fig. 4 is a front view of the holder with the cup removed therefrom.

35 The cup is denoted by 1, and is made of waxed paper or other suitable waterproof material. The cup is conical in form and is normally collapsed and has an unsealed side. The holder which is arranged to pinch the 40 side edges of the cup together to seal the side of the cup, is constructed as follows:

Two jaws 2 and 3 are hinged together at 4, and are provided at their free ends with longitudinally extended coacting surfaces 5, 45 6, from which project laterally curved sustaining arms 7, 8. The jaw 2 is provided with a cup positioning device which is herein shown as a laterally extended pin 9, near the bottoms of the jaws 2, 3. The coacting surfaces 5 and 6 of the jaws 2 and 3, are provided the one with a tongue 10 and the other with a groove 11, for receiving between them the free side edges of the cup 1.

50 The edges of the holder are held normally open by any suitable means, such, for ex-

ample, as one or more coil springs 12 surrounding one or both of the pins 13, 14, the heads of which pins serve as stops for limiting the outward or opening movement of the jaws.

In operation, the cup is inserted into position within the holder with the outer edges of its pointed bottom resting on the pin 9 and the free edges of its sides inserted between the surfaces 5 and 6 of the jaws 2 and 3. The jaws are then closed, thus pinching the side edges of the cup together and sealing the side of the cup. As water or other liquid is poured into the cup, the cup will be expanded into the form shown in Figs. 2 and 3, the arms 7 and 8 serving to sustain the walls of the cup and prevent the cup from collapsing. As soon as the cup has been used, it may be readily discarded by simply permitting the jaws to open and thereby releasing the cup from its clamped engagement with the holder.

It is evident that various changes might be resorted to in the construction, form and arrangement of the several parts without departing from the spirit and scope of my invention; hence I do not wish to limit myself strictly to the structure herein shown and described, but

What I claim is:

1. A holder for drinking cups having free side edges comprising means for pinching the side edges of the cup together to seal the same.

2. A holder for drinking cups having free side edges, comprising means for pinching the side edges of the cup together to seal the same and positioning means for the cup.

3. A holder for drinking cups having free side edges comprising means for pinching the side edges of the cup together to seal the same and means for sustaining the walls of the cup when the cup is filled.

4. A holder for drinking cups having free side edges comprising means for pinching the side edges of the cup together to seal the same, means for sustaining the walls of the cup when the cup is filled and positioning means for the cup.

5. A holder for drinking cups having free side edges comprising jaws for pinching the side edges of the cup together to seal the same.

6. A holder for drinking cups having free side edges comprising jaws for pinching the

side edges of the cup together to seal the same and means for positioning the cup in the holder.

7. A holder for drinking cups having free side edges comprising jaws for pinching the side edges of the cup together to seal the same and means for sustaining the walls of the cup when the cup is filled.

8. A holder for drinking cups having free side edges comprising jaws for pinching the side edges of the cup together to seal the same, means for positioning the cup in the holder and means for sustaining the walls of the cup when the cup is filled.

15 9. A holder for drinking cups having free side edges comprising two jaws for pinching the side edges of the cup together to seal the same, said jaws being provided with sustaining arms which coact to support the side walls of the cup when the cup is filled.

10. A holder for drinking cups having free side edges comprising two jaws for pinching the side edges of the cup together to seal the same, means tending to open the jaws and means limiting the opening movement of the jaws.

25 11. A holder for conical-shaped drinking

cups having free side edges comprising jaws for pinching the side edges of the cup together to seal the same and a pin carried by one of the jaws for positioning the cup within the holder.

12. A holder for drinking cups having unsealed sides, said holder having jaws arranged when closed to seal the sides of the cups.

18. A holder for drinking cups having unsealed sides, said holder having two jaws provided with coacting surfaces for sealing the sides of the cup and surfaces for sustaining the walls of the cup when filled.

14. A holder for drinking cups having unsealed sides, said holder having two jaws arranged when closed to seal the sides of the cups, and cup positioning means.

In testimony, that I claim the foregoing as my invention, I have signed my name in presence of two witnesses, this eighth day of February 1912.

CASPAR METTLER.
